UNITED STATES PATENT OFFICE.

GEORGE DENNY WALKER, OF HOLYOKE, MASSACHUSETTS, ASSIGNOR OF
ONE-HALF TO MICHAEL J. KELLEY, OF SAME PLACE.

DEVICE FOR FASTENING, OPENING, AND HOLDING DOORS FOR FIRE-ENGINE HOUSES.

SPECIFICATION forming part of Letters Patent No. 340,743, dated April 27, 1886.

Application filed January 30, 1886. Serial No. 190,274. (No model.)

To all whom it may concern:

Be it known that I, GEORGE DENNY WALKER, a citizen of the United States, residing at Holyoke, in the county of Hampden and Commonwealth of Massachusetts, have invented 5 certain new and useful Improvements in Devices for Fastening, Opening, and Holding Doors for Fire-Engine Houses and other Similar Places, of which the following is a specification.

My invention relates to improvements in devices for operating stable-doors for engine-houses and the like where it is very desirable to have the doors quickly opened and securely held in their open position; and the objects of my improvements are, first, to provide a secure fastening for the doors when closed; second, to provide means for opening all the doors instantly and simultaneously; third, to provide means for opening any door separately without releasing the other doors in the series; fourth, to provide an automatic fastening for holding the doors in their open position; and, fifth, to provide proper means of adjustment 25 for the connections which actuate the releasing device for the closed doors. I attain these objects by the mechanism illustrated in the accompanying drawings, in which—

Figure 1 is a front elevation of two closed doors with my invention attached; Fig. 2, a top view of the same in section, showing also by dotted lines the doors in their open position; Figs. 3 to 11, inclusive, detail views, on a larger scale, of the parts of the apparatus indicated in Figs. 1 and 2.

Similar letters refer to like parts throughout the several views.

In Fig. 1 the two doors A A are secured to the wall B by the hinges a a a a. Here the free edge of each door is attached to the fastening-pin C. (Shown on a larger scale in Fig. 6.) Said pins C engage with the releasing-pieces D D. (Shown in detail in Figs. 7 and 8.) From these releasing devices D D the rods d d pass 45 through the floor, which is indicated in section at E, and are attached to the bell-cranks F F. From these cranks a rod, G, passes to another similar bell-crank at H, which may be moved by a rod, I, connected to a suitable lever-han- 50 die, as J, by which motion may be given through the cranks and rods to the releasing

devices, which are hereinafter described in detail.

Nearer to the center of the doors than the fastening-pins C C are the holding-pins K K. (Shown on a larger scale in Fig. 5.) These engage with the holding-pieces L L, to fasten and hold the doors in their open position when released. The holding-pieces L L are shown in detail in Figs. 3 and 4.

Many of the parts of the releasing device D are similar to those of the holding device L.

The holding device will be first described. In Figs. 3 and 4, e is the case or body of the device, having a cover, f. The bottom of the case has a flange, g, for attaching it to the wall B. Above this the case is cylindrical and contains a spiral spring, h. Above the spring is a flexible washer, i, of leather or other suitable material, and an iron washer, k. Within the spring is a wooden stop, l. The cover f has the circular hole m, through which the holding-pin K, Fig. 5, can enter. Between the cover f and the case e is a rectangular space in which are the slides n and o. Said slides are removed from Fig. 4, and are shown separately in Fig. 9. The two slides are pressed together by the spiral springs p p, which are steadied by the pins q q, which are fixed in the ends of the cover f. When the rounded head of the pin K strikes between the ends of the slides, it forces them apart, presses down the washers i k upon the spring h, and thus the pin K enters far enough to allow the slides to close around the neck of the pin under its head, the circle formed by the ends of the slide being smaller than the diameter of the head of the pin. The slides have arms r s, which may be acted upon by a cam-lever, t. By pressing down the handle of the lever the arms are forced apart, thus opening the slides and releasing the pin. The lever t turns upon a small pin at u, as shown. When the pin K enters the case, it is prevented from going too far by means of the stop l.

In the releasing device, Figs. 7 and 8, the construction is similar to that just described. The case is made without a bottom flange, so that it can be set in a hole in the wall B, as shown. It contains a spring, washers, stop, and slides, as already described. The cam-lever has attached to its outer end a connecting-

piece, *v*, for the purpose of providing adjustment for the rod *d*, which transmits motion to it. The piece *v* is hollow, to leave a space for the end of the rod and a nut, as shown. A 5 flange, *w*, through which the rod *d* passes, is secured to the bottom of *v*. By removing the flange *w* the nut can be screwed on the rod to adjust it, and the arrangement also provides means for opening the slides by means of the 10 cam-lever without affecting the rod *d*.

The bell-crank F, Figs. 10 and 11, are provided with eyes *x*, fitted with set-screws *y*, for the purpose of allowing the rod *G* to pass through said eyes and be gripped by the set-screws *x* in any desired position of the cranks, 15 to provide for adjustment of the various parts connected.

The operation of the apparatus is as follows: Suppose the parts first to be in the position 20 indicated by full lines in Fig. 2—that is, with the doors closed. The pins *C C* are in the pieces *D D*, held there by the slides *n o*, and pressing down upon the springs *h*. If it is desired to instantly open the two doors, then 25 the handle *J* is moved, which, acting through rods *I*, *G*, and *d d*, and the intermediate cranks, draws down the cam-levers *t t* and releases the pins *C C*. Then the reaction of the 30 springs *h* throws the doors open, the pins *K* engage with the pieces *L L*, and the doors are held open. The lesser distance of *K* than *C* from the hinge gives a leverage which insures the compression of the springs in the holding pieces *L L* when the doors are thrown 35 open. It is obvious that any number of doors may be arranged in this manner to open si-

multaneously, and that any number of handles, like *J*, may be placed in various parts of the building, so that the apparatus may be put in operation from any required point.

If it is desired to open a single door without disturbing the others, it may be done by depressing the cam-lever *t* of the device *D*, the space in the connection *v* preventing action upon the rod *d*. In a similar manner, when it 45 is desired to close the doors the cam-levers of the holding devices *L* are depressed, and thus the pins *K* released, when the doors may be pushed shut, and will be held by the pieces *D* 50 *D*, ready for a repetition of the operation described.

Having thus described my invention, what I desire to claim and secure by Letters Patent is—

1. In a door-operating device, the combination of the pins *C* and *K*, the releasing and holding devices *D* and *L*, and the rods, bell-crank, and levers, substantially as and for the purpose described.

2. In a door fastening and releasing device, 60 the combination of the slides *n o*, cam-lever *t*, pin *K*, and spring *h*, substantially as and for the purpose set forth.

3. In a door-operating device, the combination of the connecting-piece *v*, bell-crank 65 with eyes *x*, and set-screws *y*, and the connecting-rods therefor, all substantially as and for the purpose described.

GEORGE DENNY WALKER.
